UNITED STATES PATENT OFFICE.

CHARLES P. BEISEL, OF EAST CAMBRIDGE, MASSACHUSETTS.

TRAP.

1,335,359.

Specification of Letters Patent. Patented Mar. 30, 1920.

Application filed August 25, 1919. Serial No. 319,528.

To all whom it may concern:

Be it known that I, CHARLES P. BEISEL, a citizen of the United States, residing at East Cambridge, in the county of Middlesex 5 and State of Massachusetts, have invented a new and useful Trap, of which the following is a specification.

This invention relates to traps for rats, mice and other rodents, and more particularly to an attachment to be applied to a box, wash boiler or other container by the purchaser and which, after being so applied, will constitute an efficient means for trapping the rodents, allowing them to enter the 15 container easily but preventing egress.

Another object is to provide means whereby the rodents can be subjected gradually to opposition in passing into the container and be allowed to freely leave the container until 20 accustomed to the partial obstructions, after which the attachment can be set so as to prevent the rodents from leaving the container.

A further object is to provide a simple 25 and efficient attachment which can easily be connected to a wooden or a metal container, and the parts of which are so made that they will not readily get out of order.

Another object is to provide means whereby 30 the parts can be held inactive to allow free movement of the rodents into and out of the container.

With the foregoing and other objects in view which will appear as the description 35 proceeds, the invention consists of certain novel details of construction and combinations of parts which will be hereinafter more fully described and pointed out in the 40 claims, it being understood that various changes may be made in the construction and arrangement of the parts without departing from the spirit or sacrificing any of the advantages of the invention as set forth in the appended claims.

45 In the accompanying drawing, which is a perspective view of a trap with parts broken away, the preferred form of the invention has been shown.

Referring to the drawing by characters of 50 reference 1 designates a sheet metal frame having flanges 2 extending backwardly from the inner edges of the sides thereof while projecting backwardly from the inner edge of the bottom of said frame is a lip 3. A 55 fastening tongue 4 is extended backwardly from the upper portion of the frame at the

center of the inner edge thereof and sleeves 5 are formed integral with said edge at opposite sides of the tongue 4. The outer corners of the frame are slit to form backwardly extending attaching tongues 6.

Supported by and pivotally connected to the flanges 2 is a bail 7 adapted, when lowered, to extend under the lip 3. Loosely mounted in the intermediate portion of this bail are hangers 8. U-shaped guard fingers 9 are pivotally mounted in the sleeves 5 and have suitably pointed free ends. These guard fingers are of such length that, when hanging downwardly, they will extend entirely across the opening in the frame 1 and rest against the lip 3.

The device hereinbefore described is adapted to be sold to the user who after selecting a suitable container, either of wood or of metal, cuts a hole therein of about the same size as the opening in the frame 1. If the container is of wood, as indicated at C in the drawing, the tongues 6 can be driven back into the wall of the container and the frame 1 can be fastened by tacks driven through openings in the frame 1, as indicated at 10. One or more of these attachments can be combined with a single container C. In the form shown in the drawing 25 two attachments are used. If the container is of metal slits can be cut therein adjacent the opening and the tongues 6 can be inserted into the slits and bent back, thus to attach the frame 1 to the container in a 30 manner that is obvious and does not need specific illustration.

After the device has been attached to a container the bail 7 is swung upwardly into engagement with the catch 4 and will support the guard fingers 9 in raised position as shown at the right of the drawing. The hangers 8 can be slid to the sides of the frame 1 so as not to obstruct the opening. Bait can then be placed in the container and the rodents will have free access thereto and can pass from the container readily. After the user of the trap concludes that the rodents have become accustomed to entering and leaving the container the hangers 8 are 105 slid to position across the opening in the frame 1 and bait is placed in the container. The rodents will in time find that they can pass the hangers by pushing them inwardly or outwardly and will soon become accustomed thereto. The container is again baited and the bail 7 lowered. This allows the 110

guard fingers 9 to move downwardly and the rodents, due to their becoming accustomed to the hangers 8, will not hesitate to press against the guard fingers and pass into the 5 container where they will be trapped by said fingers.

What is claimed is:—

1. A trap attachment for containers including a frame, guard fingers carried there- 10 by and adapted to swing downwardly across the frame, means for supporting the fingers in raised position, and adjustable hangers suspended from said means.

2. A trap attachment for containers in- 15 cluding a frame, guard fingers connected thereto and adapted to swing downwardly across the opening in the frame, a supporting bail for holding the fingers raised from the opening in the frame, means for holding 20 the bail in holding position, and hangers adjustably mounted on the bail.

3. A trap including a frame, backwardly extending side flanges thereon, a lip extending backwardly from the bottom portion of

the frame, guard fingers hung from the top 25 portion of the frame, and means suspended from the side flanges for supporting the fingers in elevated position.

4. A trap attachment for containers in- 30 cluding a frame, side flanges extending backwardly from the frame, a lip extending backwardly from the bottom portion of the frame, a fastening tongue extending back- 35 wardly from the top portion of the frame, guard fingers suspended from the top portion of the frame, and a supporting bail connected to the flanges and movable upwardly against the fingers and into engage- 40 ment with the tongue to support the fingers in elevated positions, said fingers when down bearing against the lip.

In testimony that I claim the foregoing as my own, I have hereto affixed my signature in the presence of a witness.

CHARLES P. BEISEL.

Witness:

HERBERT D. LAWSON.
